UNITED STATES PATENT OFFICE.

RUDOLF P. BRIESEMEISTER, OF NEW YORK, N. Y.

DESIGN FOR AN ELECTRICAL ADAPTER.

• 58,066.

Specification for Design.

Patented June 7, 1921.

Application filed December 31, 1920. Serial No. 434,372. Term of patent 3½ years.

To all whom it may concern:

Be it known that I, RUDOLF P. BRIESEMEISTER, a citizen of Germany, and a resident of the city of New York, county of Bronx, and State of New York, have invented a new, original, and ornamental Design for Electrical Adapters, of which the following is a specification, reference being

had to the accompanying drawing, forming part thereof.

The figure is a side view of an electrical adapter showing my new design.

I claim:

The ornamental design for an electrical adapter as shown.

RUDOLF P. BRIESEMEISTER.
